UNITED STATES PATENT OFFICE.

JOSEPH L. CHANTEMERLE, OF TURTLE CREEK, PENNSYLVANIA, ASSIGNOR TO WESTINGHOUSE ELECTRIC AND MANUFACTURING COMPANY, A CORPORATION OF PENNSYLVANIA.

BRUSH HOLDER.

Application filed March 14, 1918. Serial No. 222,454.

To all whom it may concern:

Be it known that I, JOSEPH L. CHANTEMERLE, a citizen of the United States, and a resident of Turtle Creek, in the county of 5 Allegheny and State of Pennsylvania, have invented a new and useful Improvement in Brush Holders, of which the following is a specification.

My invention relates to dynamo-electric 10 machines, and it has particular relations to brush holders adapted for use thereon.

One object of my invention is to provide a brush holder which may be conveniently and inexpensively manufactured from a 15 single piece of sheet metal and which shall be strong and durable in operation.

Another object of my invention is to provide a means for mounting the pressure-producing spring by which it shall be firmly held in position during operation of the 20 machine and from which it may easily be removed and replaced without removing the brush holder from the machine.

The structure of this application is an improvement upon the structure shown in 25 Patent 1,168,021, granted to C. B. Mills on January 11, 1916.

Heretofore, as shown in the patent to Mills, sheet-steel brush holders have been 30 formed of two pieces of metal so bent that one U-shaped piece fits within another of similar contour to constitute the brush box. Also, the spring is held, by projections from the sheet-metal parts, in such manner that 35 the brush holder must be removed from the machine in order to replace a broken or defective spring. In my structure, these two disadvantages are overcome and approximately a 50% saving in material is effected.

40 Referring to the accompanying drawing, Fig. 1 is a view, partially in elevation and partially in section, of a portion of a dynamo-electric machine equipped with a brush-holder constructed in accordance with 45 my invention; and Fig. 2 is a detail perspective view of the brush-holder.

Referring more particularly to the drawings, I have shown a dynamo-electric machine 1 comprising a stator 2 and a rotor 3 50 which is mounted upon a shaft 4, one bearing of which is supported by an end-bracket 5. The rotor 3 is provided with a commutator cylinder 6 upon which brushes 7, that are mounted in a brush-holder 8, are

adapted to bear. The brush-holder 8 consists of a single piece of sheet metal, one portion 10 of which is bent to substantially U-shaped in order to receive the brush 7 and another portion of which comprises three projecting members 11, 12 and 13 that are integral with the main body of the brush holder 8 and extend at right angles thereto. A spring 14, which exerts pressure upon the brush 7, is secured, at one end, to the brush holder 8 by means of the projections 11 and 12 which are provided with notches 11^a and 12^a into which the spring is pressed by the members 13 that is disposed intermediate the projections 11 and 12.

The brush 7 is enclosed on three sides 70 by the U-shaped portion 10 of the brush holder 8 and on the fourth side by the support 9 to which the brush holder is attached. The support 9 may be a metallic support for use in alternating-current machines or it may be composed of insulating material for use in direct-current machines. Also, in alternating-current machines, the brush boxes may be attached directly to the end bracket 5. An electrical 75 connection is established between the brush 7 and a terminal 15 by means of a flexible connection 16, so that the member supporting the brush box need not be of conducting material.

80 From the foregoing description, it will be understood that the spring may easily be disconnected from the brush holder 8 without detaching it from its support and that the spring will be securely held thereby at 85 all times. It will also be apparent that my brush-holder is of novel design in that it employs the supporting base 9, which may be a separate member or a portion of the end bracket 5, as a portion of the brush 90 box. Since, by the use of my invention, it is unnecessary to remove the brush holder from its support unless the brush-holder itself becomes broken, which rarely happens, it may be fastened to its support by rivets, 95 as shown at 17. This eliminates the possibility of the brush working loose and moving so as to form a poor contact with its coating bearing surface or becoming disengaged and getting between rotating and 100 stationary parts, thus causing damage to the machine.

105 While I have shown my invention in its

preferred form, it will be obvious to those skilled in the art that it is not so limited but is susceptible of various minor changes and modifications within the scope of the 5 appended claims.

I claim as my invention:

1. In a brush-holder, a spring adapted to exert pressure upon the brush and holding means for said spring comprising two 10 spaced members on one side of said spring and a third member disposed on the opposite side thereof and adapted to exert pressure thereupon at a point intermediate said two spaced members.
15. 2. In a brush holder, a spring adapted to exert pressure upon the brush and holding means for said spring comprising two spaced members on one side of said spring and a third member mounted intermediate 20 said two members and disposed on the opposite side of said spring and adapted to exert a force thereupon.
25. 3. In a one-piece brush-holder, a spring adapted to exert pressure upon the brush and holding means for said spring comprising three spaced projections integral with said brush holder but extending at right angles thereto, two of said projections having notches in one side adapted to receive

said spring and the third member being 30 adapted to hold said spring in said notches.

4. In a one-piece brush holder, a spring adapted to exert pressure upon the brush and mounting means for said spring comprising two juxtaposed members having 35 notches disposed in side-by-side relation on one side of said spring, and a third member disposed on the opposite side of the spring to hold it in said notches.

5. In a one-piece brush holder, two juxtaposed members in side-by-side relation having notches in one side, a spring adapted to exert pressure on the brush and having one end disposed in said notches, and a member 40 for holding said spring end in said notches. 45

6. In a one-piece brush holder, two juxtaposed members in side-by-side relation having notches in one side, a spring adapted to exert pressure on the brush and having one end disposed in said notches, and a member 50 adapted to exert pressure on said spring at a point intermediate said two juxtaposed members.

In testimony whereof, I have hereunto subscribed my name this 7th day of March, 55 1918.

JOSEPH L. CHANTEMERLE.
